UNITED STATES PATENT OFFICE.

LEE S. CHADWICK, OF CLEVELAND, OHIO, ASSIGNOR TO THE CLEVELAND METAL PRODUCTS COMPANY, OF CLEVELAND, OHIO, A CORPORATION OF OHIO.

OIL BURNER.

Application filed April 17, 1920. Serial No. 374,555.

To all whom it may concern:

Be it known that I, LEE S. CHADWICK, a citizen of the United States, residing at Cleveland, in the county of Cuyahoga and State of Ohio, have invented a certain new and useful Improvement in Oil Burners, of which the following is a full, clear, and exact description, reference being had to the accompanying drawings.

10 This invention relates to improvements in that class of oil burners wherein wicks, particularly of the tubular variety, are employed; and it has to do more especially with a novel form of wick stop and an indicator 15 for showing the elevation of the wick at any time.

The objects are to provide an efficient, yet simple and inexpensive, wick stop that may be easily emplaced and locked within the 20 burner and as conveniently removed therefrom; that will maintain the wick even; that is of a design lending itself readily to sheet metal construction and wherein the elements are connected together by interlocking integral parts; and, further, to provide a self-adjusting indicator which adapts itself to the variable length of the wick as the latter 25 is consumed, and which is simple, cheap and durable, and of such a nature as to be practically 30 self-explanatory and therefore capable of being readily understood by novices.

These objects are attained in the construction illustrated in the drawings accompanying and forming a part hereof, and 35 wherein Fig. 1 is a sectional side elevation of a burner embodying my invention; Fig. 2 is a plan of the burner with the commingling tubes omitted; Fig. 3 is a side elevational view of the wick stop; Fig. 4 is a 40 section inside the operating handle of the wick raiser on the line 4—4 of Fig. 2, and showing the indicator in detail; and Fig. 5 is a perspective view of the index pointer of the indicator.

45 The particular burner wherein I have elected to show my improvements incorporated is of a well known type and comprises inner and outer wick tubes 1 and 2, which are spaced apart and are connected together 50 with a liquid tight joint at their lower end so as to enclose an annular wick space which has communication through a tubular connection 3 with a supply pipe 4, the burner being securely held to the pipe on one side

by means of a clamp 5, which embraces the 55 connection 3 and supply pipe 4, and on its opposite side, by a hook 6.

The inner and outer wick tubes are provided near their upper ends with ledges 10 and 11, respectively, and secured to the inner 60 wick tube 1 immediately below the ledge 10 is an anchorage element or spider 12. The peripheral portion of the spider is connected, through a frustoconical section 13, with a horizontal portion 15 having slots 16, the 65 central portion of the spider being depressed or dished to a depth considerably below the plane of the horizontal portion 15. This latter portion and the frustoconical portion 13 are provided with liberal sized air openings 17 and 18, respectively.

The wick stop, designated generally by the numeral 20 is shown as made up of three parts, the first, a diaphragm, having an annular portion 21 which is flared outwardly 75 and slightly upwardly from a depressed central portion 22 and is surrounded by an annular depression 23 beyond which it is provided with a peripheral flange 24 from which the stop fingers 25 rise. The depressed portion 23 is designed to rest upon the ledge 10, and when in such position the fingers 25 extend upwardly and outwardly over the wick space. The annular portion 21 is provided with air openings 26. Secured 80 with its upper edge within the angle between the annular portion 21 and the depressed portion 22 is the second part consisting of a crown 30 which terminates at its lower end in locking fingers 31 that are designed to project through the slots 16 of the horizontal portion 15 of spider 12, and these fingers have laterally opening notches 32 which are adapted to embrace the parts of the horizontal portion 15 between the slots 85 16 when the stop 20 is turned by means of a member 33 that is secured to it within the depression 22 and constitutes the third part 90 of the wick stop. This member, though of a sheet metal stamping, is made to resemble 95 a winged nut so as to suggest to the user that the same is to be turned. In placing the wick stop in position it is grasped by the member 33 and lowered into position 100 with the fingers 30 projecting through the slots 16 and when the depressed portion 23 engages the ledge 10 the stop is turned to secure it to the spider 12. It will be observed

that the lower sides of the notches 32 are slightly inclined so as to operate with a camming action against the cooperating parts of the spider 12 and draw the elements 5 firmly together. The crown 30 and the member 33 may be secured to the first mentioned part of the stop by tongues 35 that are carried by said crown and member and projected through slots in the diaphragm. 10 Commingling tubes 40 and 41 are arranged to rest with their respective lower ends within the depressed portion 23 of the wick stop and upon the ledge 11 of the outer wick tube, as clearly illustrated in 15 Fig. 1. The commingling tubes are enclosed within a drum 43, and the inner commingling tube, near its lower end is provided with a head 44 that supports, at its center, a thimble 45. The thimble receives the upper end of a rod 46 that is guided through a central aperture 47 of spider 12, passing through an aperture of the wick stop, and at its lower end is turned forwardly and projected through a slot 48 of a plate 49 which 25 depends from the burner. Beyond the front of the plate the rod is equipped with a handle 50 by means of which the rod and the commingling tubes and drum may be raised; and they may be retained in elevated position 30 by engaging the forwardly turned portion of the rod within an offset 51 of the slot. The raising of the commingling tubes is for the obvious purpose of affording access to the wick for lighting.

35 A wick 55 occupies the space between the wick tubes and is equipped with the usual carrier 56 that cooperates with the star wheels 57 secured to the wick raising spindle 58. The star wheels, and the spindle 40 throughout the greater part of its length, are enclosed within a casing 60 that is supported and spaced from the outer wick tube by a bracket 61. A dial 62 is secured to the outer end of the tubular portion of the casing 60 and the same is surrounded by a prominent bead 63. It will be noted in Fig. 45 that the dial bears the words "Out", "Low", "Medium", and "High" and associated with the first is an arrow to indicate that to turn the burner out it should be turned to the limit of its movement in the direction indicated by the arrow. Frictionally engaged about the protruding end of the spindle 58 is the split sleeve 65 of a one-piece sheet metal pointer 66, the construction of which is better illustrated in Fig. 5. Now, when the spindle is turned by means of the operating handle 67 in a direction to lower the wick and extinguish the flame, the 55 pointer will engage the bead of the dial and its movement will be arrested thereby considerably before the spindle ceases to rotate. When it is desired to light the burner, after the commingling tubes and drum have been 60 lifted, the spindle is turned in the opposite 65

direction as far as possible or until the wick is blocked in its upward movement by the fingers 25 of the wick stop. Also, before the spindle ceases to rotate in the latter direction, the pointer 66 engages the bead at the opposite end of the dial and is held thereby against further movement. Now, when the wick has been lighted, the spindle is rotated backwardly to the designation corresponding to the wick position desired. 75

It will be seen from this explanation that every time the burner is lighted the index finger will be set to a proper position with respect to the condition of the wick, obviating the need of resetting the index finger 80 from time to time as the wick is consumed as is the case in prevailing styles of an indicator associated with burners of the type herein disclosed.

Having thus described my invention, what I claim is:—

1. A burner of the character described comprising inner and outer wick tubes, an anchorage element within the inner wick tube, a wick stop adapted to be mounted within the upper end of the inner wick tube, said wick stop comprising a diaphragm that is formed with a central depression and having parts projecting over the wick space between the wick tubes and other parts for interlocking engagement with the anchorage element when the wick stop is turned, and an operating handle having the appearance of a winged nut situated within the aforesaid central depression and attached to the wick stop for turning the same. 95

2. In a burner involving inner and outer wick tubes and an anchorage element within the inner wick tube, a wick stop comprising a diaphragm having a central depressed portion and upwardly and outwardly extending peripheral stop fingers, and a crown applied to the underneath side of the diaphragm with its upper end surrounding and positioned by the central depressed portion of the diaphragm and involving locking fingers for cooperation with the anchorage element. 105

3. In a burner involving inner and outer wick tubes and an anchorage element within the inner wick tube, a wick stop comprising a diaphragm having a depressed central portion, a portion flaring outwardly and slightly upwardly therefrom, and surrounded by an annular depression skirted by an upwardly extending peripheral flange from which stop fingers project upwardly and outwardly, a crown applied to the underneath side of the diaphragm and having its upper end surrounding said depressed central portion, said crown having parts for interlocking engagement with the anchorage element when the wick stop is turned, and means for turning the wick stop. 115 120 125

4. In a burner involving inner and outer

wick tubes and an anchorage element within the inner wick tube, a wick stop comprising a diaphragm having a depressed central portion and stop fingers projecting upwardly and outwardly from its periphery, a crown applied to the underneath side of the diaphragm and having parts for interlocking engagement with the anchorage element when the wick stop is turned, and an operating handle attached to the diaphragm and situated within said depressed central portion.

5. In a burner involving inner and outer wick tubes and an anchorage element within the inner wick tube, a wick stop comprising a diaphragm having a central depressed portion and an upwardly extending peripheral flange from which stop fingers project upwardly and outwardly, a crown applied 15 to the lower side of the diaphragm and having its upper end engaged about the central depression thereof and attached to the diaphragm by integral tongues that are extended through slots in the latter, said 20 crown having depending portions that are situated within the depressed portion of the diaphragm and attached thereto by integral tongues that are extended through slots in the diaphragm.

6. In a burner involving inner and outer wick tubes and an anchorage element within the inner wick tube, a wick stop comprising a diaphragm having stop fingers projecting upwardly and outwardly from its periphery, a crown attached to the under side of the 35 diaphragm by integral tongues that are extended through slots in the latter, said crown having depending portions for interlocking engagement with the anchorage element when the wick stop is turned, and an operating handle attached to the diaphragm by integral tongues that are extended through slots in the latter.

7. In a burner involving inner and outer wick tubes, an anchorage element having 50 its periphery secured to the inner wick tube adjacent the upper end thereof and converging downwardly to an annular horizontal portion having relative narrow arcuate slots, and a wick stop adapted to be inserted into 55 the upper end of the inner tube and having segmental locking fingers that are ranged to be inserted through said slots and interlock with the portions of the anchorage element beyond the ends of the slots when the 60 wick stop is turned, the parts being so designed and proportioned that the wick stop is thus held positively against upward movement.

8. In a burner involving inner and outer wick tubes, the former having an inwardly

projecting ledge adjacent its upper end, an anchorage element disposed below the plane of and having its peripheral portion engaged with the under side of the aforesaid ledge, and a wick stop adapted to rest upon 70 said ledge and having depending extensions for interlocking engagement with the anchorage element when the wick stop is turned, the interengaging parts of the wick stop and anchorage element being of such 75 nature as to create a tension between the wick stop and element when the parts are interlocked.

9. In a burner involving inner and outer wick tubes, the former having an abutment 80 adjacent its upper end, an anchorage element disposed below said abutment, and a wick stop adapted to rest upon the abutment and having depending extensions for interlocking engagement with the anchorage 85 element when the wick stop is turned, the interengaging parts of the wick stop and anchorage element being of such nature as to draw the wick stop into firm engagement with the abutment when the parts are interlocked.

10. In an oil burner of the class set forth, the combination of means for limiting the upward movement of the wick, a wick raising spindle, a dial with respect to which 95 the spindle is rotatable, a pointer yieldingly engaged with the spindle and supported thereby in operative relation to the dial, the dial bearing indications designating the 100 various positions of the wick and directions to turn the wick to its lowermost position for the purpose specified, and means for restraining the movement of the pointer in both directions to less than that of the 105 spindle.

11. In an oil burner of the class set forth, the combination of means for limiting the upward movement of the wick, a wick raising spindle, a dial supported in operating 110 relation to the spindle and with respect to which the spindle is rotatable, the dial having a depressed area and bearing indications which designate the various positions of the wick and directions to turn the wick to its lowermost position as for the purpose of extinguishing the flame, and an index pointer frictionally engaged with the spindle and having a part operating over and in juxtaposition to the depressed portion of the dial 115 and arranged to engage the elevations at the ends of said depressed portion thereby to limit its movement to less than that of the spindle when the latter is turned in either direction, in one instance to raise the wick to its maximum elevation for lighting, and in the other to lower the wick to its maximum depressed position for extinguishing 120 the flame.

12. In an oil burner of the class set forth, the combination of means for limiting the 125

upward movement of the wick, a wick raising spindle, a dial with respect to which the spindle is rotatable and bearing indications designating the various positions of the wick, and an index pointer formed of a single piece of sheet metal and incorporating a vane and a split sleeve that is frictionally engaged about the spindle, the pointer being arranged to engage parts of the dial for limiting its movement to less than that of the spindle in either direction.

13. An index pointer constructed of a single piece of sheet material bent over upon itself to form a vane and having opposed portions curved outwardly to constitute a spindle embracing sleeve.

14. In an oil burner of the class set forth, the combination of a stop for arresting the upward movement of the wick, an element for raising and lowering the wick, and indicating mechanism associated with said element and comprising two parts that are movable one with respect to the other, the movable part being yieldingly engaged with said element, and means limiting the movement of said movable part to less than that

of the element when the latter is moved to the limit of its movement in either direction.

15. In an oil burner of the class set forth, the combination of a stop for arresting the upward movement of the wick, an element for raising and lowering the wick, and an indicator associated with said element for showing various positions of the wick, said indicator being frictionally adjustable with respect to the element, the latter having a range of movement in both directions in excess of that of the indicator, as and for the purpose specified.

16. In a burner of the class set forth, the combination of a stop for limiting the upward movement of the wick, means for raising and lowering the wick, and an indicator for showing the position of the wick and which automatically resets itself with respect to the wick raising and lowering means as the latter is operated thereby to compensate for the gradual consumption of the wick.

In testimony whereof, I hereunto affix my signature.

LEE S. CHADWICK.
